CLAIM

The ornamental design for a drinking container, as shown and described.

DESCRIPTION

FIG. 1 is a perspective view showing the front, right and top views of a drinking container embodying my new design; FIG. 2 is a left side elevational view thereof, the right side elevation being a mirror image of the left side as shown; FIG. 3 is a top plan view thereof; FIG. 4 is a bottom plan view thereof; FIG. 5 is a rear elevational view thereof; FIG. 6 is a front elevational view thereof; and, FIG. 7 is a perspective view similar to FIG. 1, illustrating a cap in an open position.
